UNITED STATES PATENT OFFICE.

WILLIAM BERTRAM BOLLES, OF MILWAUKEE, WISCONSIN.

FASTENING DEVICE FOR EMERGENCY-EXIT DOORS.

Application filed May 5, 1926. Serial No. 106,855.

The present invention relates to fastening devices for emergency exit doors designed particularly for use on doors such as fire-escape doors where it is not necessary to provide for access through the doors from the outside of the building.

The invention has for its object to provide a simple, effective and inexpensive fastening device which can be instantly and easily released from the inside of the building which effectively prevents opening of the doors from the outside of the building.

With the above and other objects in view the invention may be said to comprise the door fastening device as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a horizontal section through the door and its frame taken immediately above the fastening device; Fig. 2 is a section on line 2—2 of Fig. 1; Fig. 3 is a side elevation of the keeper attached to the door jamb; Figs. 4 and 5 are sectional views similar to Fig. 2 showing modified forms of the invention.

Referring to the accompanying drawings a door is indicated by the numeral 1 and is attached to the jamb 2 of the door frame by suitable hinges 3, the free edge of the door engaging with the opposite door jamb 4 when the door is in closed position. A pair of brackets 5 are attached to the inner side of the door adjacent the opposite side edges thereof at substantially the height from the floor of the usual door knob. Each of the brackets 5 has side flanges 6 extending outwardly at right angles to the plane of the door and upper and lower guard flanges 7 and 8 connecting the upper and lower edges of the flanges 6. Rigid arms 9 and 10 are mounted between the side flanges 6 of the brackets 5 and are pivotally connected to brackets by horizontal pivot pins 11, the arm 9 being mounted in the bracket adjacent the hinged edge of the door and the arm 10 being mounted in the bracket adjacent the free edge of the door. The arm 9 is provided with an elbow socket 12 and the arm 10 is provided with a T socket 13. A tubular cross bar 14 fits in the elbow socket

12 of the arm 9 and extends through the T socket 13 of the arm 10, the outer end of the bar 14 projecting beyond the end of the socket 13. A keeper 15 is rigidly secured to the jamb 4 inwardly of the door stop and this keeper is in the form of a plate which lies flat against the jamb 4 and which is secured to the jamb by means of suitable screws 17. The upper edge of the keeper plate which projects inwardly from the face of the door jamb is formed to provide an arcuate retaining portion 18 and forwardly of the retaining portion 18 is formed to provide an inclined cam portion 19 on the side of the keeper toward the door.

The retaining portion 18 of the keeper is formed substantially on an arc of a circle which has its center at the axis of the pivot 11 when the door is in closed position, the radius of the arc upon which the flange 18 is formed being substantially equal to the distance between the axis of the pivot pin 11 and the tubular cross bar 14 so that when the door is in closed position the arm 10 can be swung about its pivot with the projecting portion of the cross bar 14 in contact or close to the arcuate edge portion 18 of the keeper. The lower guard flanges 8 of the brackets 5 limit the movement of the arms 9 and 10 and serve to normally support these arms in substantially horizontal positions at right angles to the plane of the door. When the door is in closed position the weight of the cross bar 14 and arms 9 and 10 tends to move the arms down into engagement with the guard 8 and the arms are supported in horizontal positions with the projection of the bar 14 behind the flange 18 of the keeper. When the cross bar is held in this position the door is effectively held against opening from the outside but can be instantly and easily released by a person on the inside, it being simply necessary to lift the cross bar 14 until the projecting end thereof is lifted clear of the flange 18 to release the door. The upper guard flange 7 is a short flange between the upper edges of the side flange 6 which serves to limit the inward swinging movement of the arms 10 so that the knuckles of a person operating the bar are prevented from coming in contact with the door. In opening the door it is necessary simply to lift on the bar 14 and swing the arms 9 and 10 to substantially vertical position and then push outward on the bar, the movement of the arms from horizontal to vertical position

releasing the extension of the cross bar from the keeper so that the door is free to open. When the door is swung to closed position, the tubular cross bar 14 will engage with the inclined cam extension 19 of the keeper and will ride up this incline and over the top of the arcuate portion 18 and when the door is fully closed, the bar 14 will have been moved by gravity to locking position and will hold the door tightly against its stops.

In order to provide a more positive stop for the arms 9 and 10 and to prevent injury to the brackets 5 by impact of the arms against the guard flanges 7 and 8, the arms 15 9 and 10 are each provided with an extension 20, the inner ends of which engage with the upper guard flanges 7 when the arms are in horizontal position and with the lower guard flanges 8 when the arms are in substantially vertical position.

As shown in Fig. 4 of the drawing, the action of gravity in holding the bar 14 in its outermost position, with the supporting arms 25 9 and 10 horizontal, may be assisted by springs 21 interposed between the arms and supporting brackets.

As shown in Fig. 5 the device may be used in inverted position, in which case the springs 21 must be of sufficient strength to normally hold the supporting arms in horizontal position. When the keeper and lock bar are mounted on the jamb and door in inverted position, the lock bar is released by pushing the same downwardly and the bar is forced upwardly to locking position by the springs 21 when the door is closed.

I claim—

1. In a device of the character described, the combination with a hinged door and its frame, of a keeper attached to the frame member opposite that to which the door is hinged and projecting into the door opening, rigid arms pivoted to the inner side of the door adjacent opposite edges thereof to swing vertically between the frame members and a cross bar connecting the outer ends of said arms, the arm adjacent the free edge of the door having a projection outwardly of its pivot which is adapted to engage with 50 said keeper.

2. In a device of the character described, the combination with a hinged door and its frame, of a keeper attached to the frame member opposite that to which the door is hinged, rigid arms pivoted to the inner side 55 of the door adjacent opposite edges thereof to swing vertically and a cross bar connecting the outer ends of said arms, said cross bar projecting past the arm adjacent the free edge of the door to engage with said keeper. 60

3. In a device of the character described the combination with a hinged door and its frame, of a pair of brackets secured to the inner face of the door, one adjacent the hinged edge and one adjacent the free edge 65 thereof, a rigid arm connected to each of the brackets by a horizontal pivot, the arm adjacent the free edge of the door having a lateral projection, means carried by said brackets for normally holding said arms in 70 horizontal positions, a cross bar connecting said arms, and a keeper secured to the frame member with which the free edge of the door engages, said keeper being so positioned as to be between said projection and the door when the door is closed and the arms are in horizontal position.

4. In a device of the character described the combination with a hinged door and its frame, of a pair of brackets secured to the inner face of the door, one adjacent the hinged edge and one adjacent the free edge thereof, a rigid arm connected to each of the brackets by a horizontal pivot, the arm adjacent the free edge of the door having a 85 lateral projection, means carried by said brackets for normally holding said arms in horizontal positions, a cross bar connecting said arms, and a keeper secured to the frame member with which the free edge of the 90 door engages, said keeper being so positioned as to be between said projection and the door when the door is closed and the arms are in horizontal position, and said keeper having a cam face on the side toward the door over 95 which the projection is adapted to ride during the final closing movement of the door.

In testimony whereof, I hereunto affix my signature.

WILLIAM BERTRAM BOLLES.
